(57) **CLAIM**

The ornamental design for a coating film transfer tool, as shown and described.

DESCRIPTION

FIG. 1 is a front view of the design for a coating film transfer tool according to the invention.

FIG. 2 is a rear view of the design according to the invention.

FIG. 3 is a top view of the design according to the invention.

FIG. 4 is a bottom view of the design according to the invention.

FIG. 5 is a right side view of the design according to the invention; and,

FIG. 6 is a left side view of the design according to the invention.

The elements shown in broken lines are for illustrative purposes only and form no part of the claimed design.

The portions shown in diagonal lines are transparent.
